UNITED STATES PATENT OFFICE.

CARL HOFFMAN, OF ALLENTOWN, PENNSYLVANIA.

LOCK.

1,388,713.

Specification of Letters Patent. Patented Aug. 23, 1921.

Application filed July 16, 1920. Serial No. 396,697.

To all whom it may concern:

Be it known that I, CARL HOFFMAN, of Allentown, in the county of Lehigh and State of Pennsylvania, have invented certain new and useful Improvements in Locks; and I do hereby declare the following to be a full, clear, and exact description of the invention, such as will enable others skilled in the art to which it appertains to make and use the same.

My invention relates to locks and is of the type where the locking and latching functions are effected by a single member on the door coöoperating with a keeper on the door casing. The object of my invention is to provide a simple and highly efficient lock with but a minimum number of parts which are so arranged that the lock-latch is readily operable from inside and outside the door by means of a handled spindle; may be locked on the inside to prevent manipulation from without; may be locked from outside by means of a key which sets a control mechanism so that the lock-latch may not be moved save by an appropriate key which must first be turned to dislodge a stop from locking engagement with the lock-latch lever and then be brought into engagement with a tumbler controlled actuating slide by which the lever is moved to retract the lock-latch.

In the drawings, Figure 1 is a view in perspective of a portion of the door, viewed from the inside, with my improved lock applied thereto. Fig. 2 is an elevation with one of the casing plates removed to show the operating mechanism. Fig. 3 is a detail showing the key cylinder and the bit end of the key. Fig. 4 is a side elevation of a portion of the operating lever.

While my improved lock is applicable to any door I have designed it primarily for use with store doors. A casing 1 with the usual edge and side plates is mortised in a door and is provided with necessary openings for the projection of the lock-latch 2 and for access to the control mechanism by means of a handle and a key. The lock-latch has an inwardly extending portion 3 with a projecting stud 4 with which a hook-like finger 5 of an operating lever 6 is designed to have sliding engagement to retract the lock-latch against the tension of its spring 7. This lever is of peculiar formation. It has two arms 8 and 9, the latter

being longer than the arm 8, the pivotal connection of the lever with the casing being at the extreme end of the arm 9, as indicated at 10. A cut-out 12 in the arm 9 is adapted to receive a stop block 13 which when moved into this cut-out effectively prevents any movement of the lever. The stop block has talons 14, 15, with which the bit of a key is designed to engage to raise and lower the stop block, the latter being held in either of its two positions by a spring held tumbler 17 which is in locked engagement with the block, it being necessary to first move the tumbler before the stop block can be actuated. A winged spindle 18 operable by appropriate handles 19 on the inside and outside of the door is one means for turning the lever 6 to retract the lock-latch, the wings 20 of the spindle engaging the arm 9, as shown in Fig. 2. The arm 8 at its extreme end carries a hinged plate 21 which forms a continuation of the arm. To this plate is secured a lever 22 which is bent so as to lie in spaced parallelism with the arm 8, a spring 23 interposed between the lever and arm normally maintaining the plate 21 in the same plane with the arm 8. A projection 24 on the lever extends laterally into a semi-circular recess 25 of the lever 6 and when moved longitudinally of the recess will rock the plate 21 and cause it to assume a slightly slanting position relative to the arm 8 so that in this deflected position of the plate as indicated in dotted lines, Fig. 4, a tumbler actuated slide, to be hereinafter described, cannot operatively engage the plate. For the purpose of moving the lever 22 as just described I employ a stop pin 26 frictionally held in the lock case and operable from inside the door. This stop pin when moved inward first presses on the projection 24 of the lever 22 and then takes in the recess 25 effectively locking the lever 6 against movement. This stop pin may also be employed to hold the lock-latch permanently retracted, the pin taking in a recess 27 of the lock-latch for this purpose.

At 30 I have indicated a control slide which when moved in one direction by engagement of the bit of the key with its talon 31 will contact with the plate 21 and cause the lever 6 to turn on its pivot to retract the bolt. This control slide is locked against movement in either direction by

tumblers 33, the spring 7 which co-operates with the lock latch serving to tension these tumblers.

A cylinder 35 having a longitudinal slot 36 extending part way through the cylinder forms the guide for the key 16. At its inner end this cylinder carries a hinged finger-hold 37, the latter when turned at right angles to the cylinder and into engagement 10 with a stud 38 on the door positioning the cylinder so that a key cannot be inserted therein, the slot of the cylinder when in this position being out of line with the key-way. This forms a means for preventing manipulation of the lock from the outside by means 15 of a key or some foreign tool.

If it be desired the lever 6 may be provided with an extension at its upper end for actuating a signal to indicate opening 20 of the door. I have shown such a connection in Fig. 2, a bell being indicated at 40, the extension of the lever at 41, and suitable gearing at 42.

In the use of my improved lock, and assuming the parts to be in the position shown 25 in Fig. 2, turning of the spindle 18 from either inside or outside the door will cause one of the wings 20 to engage the arm 9 of the lever 6 and turn the lever on its pivot 30 causing a retraction of the lock-latch through engagement of the finger 5 with the stud 4. This movement is also effective to sound the bell through the mechanism shown for that purpose. If it be desired to hold 35 the lock-latch in retracted position it is only necessary to withdraw it from engagement with its keeper by means of the handle, as suggested, and to push in on the stop pin 26 so that it will take in the recess 27 and 40 hold the lock-latch against the tension of its spring. With the parts in operable position, if it is desired to secure the lock-latch against manipulation from without the cylinder 35 must first be turned so that its slot 45 36 is at the bottom. The key is then inserted and turned so that its bit will engage the tumbler 17 to remove it from locking engagement with the stop block 13, further turning of the key bringing the bit into contact 50 with the talons of the stop block to move it up into the cut-out 12 of the arm 9. The key is then withdrawn, but before it is entirely removed from the cylinder it may be given a turn to place the slot of the cylinder in reverse of the correct position for 55 operation of the lock. To release the lock-latch from the outside by means of the key, the cylinder 35 must be positioned with its slot at the top, the key inserted and turned 60 so as to move the tumbler 17 and the stop block 13, the latter from engagement with the lever 6, continued turning of the key then bringing its bit into engagement with the tumblers 33 for unlocking the slide 30 65 and then moving the slide to contact with

the plate 21 which causes the turning of the lever 6 and retraction of the lock-latch. Locking of the parts from within so as to prevent any manipulation from without either by the handle or key is effected by 70 pressing inwardly on the stop pin 26 which not only removes the plate 21 from position to be engaged by the slide 30 but also secures the lever 6 against movement. It will be appreciated that even though a key 75 or other instrument may be inserted and the tumbler actuated slide 30 moved its movement is ineffective since the plate 21 is deflected from the path of the slide 30. Additional security may be given by turning the 80 cylinder 35 and fastening its finger-hold 37 on the stud 38.

I claim as my invention:

1. In a lock, a tensioned lock-latch, an actuating lever therefor, a handled spindle 85 for operating said lever, tumbler controlled means for engaging and moving said lever to retract said lock-latch, and a tumbler controlled means for locking said lever against movement, in combination with a key for 90 effecting movement of each of said last mentioned means.

2. In a lock, a tensioned lock-latch, an actuating lever therefor, a handled spindle for operating said lever, a tumbler controlled slide for engaging said lever to move it to retract said lock-latch, means for deflecting said lever from the path of said slide, and a tumbler controlled stop for locking said lever against movement, in combination with a key for actuating said stop and said tumbler controlled slide. 100

3. In a lock, a tensioned lock-latch, an actuating lever therefor having a hinged portion, a handled spindle for operating 105 said lever, a tumbler controlled slide for engaging the hinged portion of said lever to retract said lock-latch, means for moving said hinged portion of the lever from the path of said slide, and a tumbler controlled stop for locking said lever against movement, in combination with a key for actuating 110 said stop and said tumbler controlled slide.

4. In a lock, a tensioned lock-latch, an actuating lever therefor, having a hinged portion, a handled spindle for operating said lever, a tumbler controlled slide for engaging the hinged portion of said lever to retract said lock-latch, a stop pin for moving 120 said hinged portion of the lever from the path of said slide, and a tumbler controlled stop block for locking said lever against movement, in combination with a key for actuating said stop block and said 125 tumbler controlled slide.

5. In a lock, a casing, a tensioned lock-latch, an actuating lever therefor having a pair of arms, one of said arms having a hinged portion, and the other of said arms 130

having a cut away portion, a handled spindle for operatively engaging said last mentioned arm, a tumbler controlled slide for engaging the hinged portion of said first 5 mentioned arm to cause said lever to retract said lock-latch, a tumbler controlled stop block for taking in the cut-away portion of said second arm to lock said lever against movement, and means in part carried by said lever and in part by the casing of the lock 10 for moving said hinged portion from the path of said slide, in combination with a key for actuating said stop block and said tumbler controlled slide.

In testimony whereof I have signed this 15 specification.

CARL HOFFMAN.
